(57) **CLAIM**

The ornamental design for a spring for mobile device holders, as shown and described.

DESCRIPTION

FIG. 1 is a perspective view of a spring for mobile device holders according to the present design;
FIG. 2 is a front elevation view thereof;
FIG. 3 is a rear elevation view thereof;
FIG. 4 is a left side view thereof;
FIG. 5 is a right side view thereof;
FIG. 6 is a top plan view thereof;
FIG. 7 is a bottom plan view thereof; and,
FIG. 8 is an exploded perspective view showing the combination between the spring for mobile device holders according to the present design and other parts of the mobile device holders wherein the broken lines showing the other parts of the mobile device holders represent unclaimed subject matter and form no part of the claimed design.
